US00D765171S

(12) **United States Design Patent** (10) **Patent No.:** **US D765,171 S**
Tattersall (45) **Date of Patent:** **** Aug. 30, 2016**

(54) **FINANCIAL CARD WITH EDGE INDICATORS**

(71) Applicant: **BANK OF AMERICA CORPORATION**, Charlotte, NC (US)

(72) Inventor: **Kenneth G. Tattersall**, Wilmington, DE (US)

(73) Assignee: **BANK OF AMERICA CORPORATION**, Charlotte, NC (US)

(**) Term: **14 Years**

(21) Appl. No.: **29/468,803**

(22) Filed: **Oct. 3, 2013**

Related U.S. Application Data

(63) Continuation of application No. 29/448,769, filed on Mar. 13, 2013.
